UNITED STATES PATENT OFFICE.

RENE R. STUDLER, OF THE UNITED STATES ARMY, WASHINGTON, DISTRICT OF COLUMBIA.

MUZZLE ATTACHMENT FOR AUTOMATIC GUNS.

Application filed April 12, 1927. Serial No. 183,153.

(GRANTED UNDER THE PROVISIONS OF THE ACT OF MARCH 3, 1883, 22 STAT. L., 625.)

The invention described herein, if patented, may be manufactured and used by or for the Government for governmental purposes without the payment to me of any 5 royalty thereon.

The subject of this invention is a muzzle attachment for automatic guns.

In employing blank ammunition having a reduced powder charge with service 10 weapons, it is customary to place an attachment at the muzzle of the gun which will serve to retard the escaping gases and thereby insure proper functioning of the operative elements of the gun. These attachments are generally provided with a restricted 15 opening to cause disintegration of the paper or wooden bullet as it leaves the muzzle. However, it frequently occurs that the bullet will become lodged in the opening 20 and with the barrel thus occluded the pressure is excessive and drives the recoiling members through the back plate of the gun. This condition in addition to damaging the gun invariably results in injury to the gunner. 25

Accordingly it is proposed in the present invention to provide a muzzle attachment in which the disintegrating plug is secured by a frangible connection.

With the foregoing and other objects in view, my invention resides in the novel arrangement and combination of parts and in the details of construction hereinafter described and claimed, it being understood 35 that changes in the precise embodiment of the invention herein disclosed may be made within the scope of what is claimed without departing from the spirit of the invention.

A practical embodiment of the invention 40 is illustrated in the accompanying drawings, wherein:

Fig. 1 is a longitudinal sectional view of the attachment with the plug in normal position;

Fig. 2 is a similar view with the plug in released position;

Figs. 3 and 4 are sectional views on the respective lines of Fig. 1.

Referring to the drawings by numerals 50 of reference:

The attachment comprises a tubular member or sleeve 5 which is externally threaded

as at 6 at its rear end for attachment to the muzzle of the gun and is internally threaded as at 7 at its forward end for the reception 55 of a stop member 8. The rear extremity of the sleeve is provided with an inturned flange 9 against which is seated a plug 10 having a restricted bore 11 of less diameter than the bore of the gun barrel and this 60 bore merges with a flared mouth 12. The plug is preferably secured to the sleeve by means of a suitable number of shear pins 13.

As the wood or paper bullet of the blank carriage is discharged through the restricted 65 bore it will be disintegrated while the gases being prevented from rapid escape will provide sufficient backward pressure to insure the normal recoil of the moving members which is necessary for automatic action 70 of the weapon.

In the event that the bullet becomes lodged in the restricted bore of the plug the gases can not escape and the pressure developed and exerted on the plug will cause the shear 75 pin 13 to be severed, allowing the plug to be moved forwardly in the sleeve until brought up against the stop member 8. During this movement the sleeve constitutes an expansion chamber and the plug will uncover a number of relief ports 14 provided 80 in the length of the sleeve for the escape of the gases.

Since the pressure has been relieved through the muzzle the recoiling members 85 will not be energized and the automatic action of the gun will be discontinued.

The stop member 8 plays an important rôle when the attachment is mounted on synchronized airplane guns as the plug will 90 be prevented from issuing and striking the blades of the propeller.

The assembly is so arranged that the replacement of the frangible connection will involve only the simple operation of removing the plug by unscrewing the stop member 95 8, removing the parts of the shear pins and reassembling.

I claim:

1. An attachment for automatic guns including a sleeve attachable at the muzzle of a gun, said sleeve provided with an inturned flange at its rear end and a plurality of ports along its length, a plug having a restricted 100

bore less than the bore of the gun, shear pins connecting the plug to the sleeve and a stop member removably attached to the forward end of the sleeve.

5. An attachment for automatic guns including a sleeve attachable at the muzzle of a gun, said sleeve provided with an inturned flange at its rear end and a plurality of ports along its length, a plug having a restricted bore less than the bore of the gun seated on the flange, and shear pins connecting the plug to the sleeve.

3. An attachment for automatic guns including a sleeve attachable at the muzzle of a gun and having a plurality of ports, a plug having a restricted bore mounted in the sleeve in the rear of the ports and a frangible connection between the plug and sleeve.

4. An attachment for automatic guns including a support attachable at the muzzle of a gun and constituting an expansion chamber having relief ports and a member having a restricted bore frangibly secured to the support in rear of the ports.

5. An attachment for automatic guns including a support attachable at the muzzle of a gun and having relief ports, a pressure receiving member in the support in rear of the ports, said member mounted for forward displacement on development of excessive pressure.

RENE R. STUDLER.
